DESIGN FOR AN ASCOT SCARF

Nathan Gold, Portland, Oreg.

Application January 14, 1942, Serial No. 105,203

Term of patent 14 years

To all whom it may concern:

Be it known that I, Nathan Gold, a citizen of the United States, residing at Portland, in the county of Multnomah and State of Oregon, have invented a new, original, and ornamental Design for an Ascot Scarf, of which the following is a specification, reference being had to the accompanying drawing, forming a part thereof wherein:

Fig. I is a plan view of an ascot scarf showing my design, and

Fig. II is a view of the ascot scarf shown in Fig. I in wearing position, drawn to a larger scale.

I claim:

The ornamental design for an ascot scarf, as shown.

NATHAN GOLD.
